UNITED STATES PATENT OFFICE.

CHARLES T. CROSBY, OF GRANTS PASS, OREGON.

IGNITING DEVICE.

1,294,625.

Specification of Letters Patent. Patented Feb. 18, 1919.

Application filed May 25, 1918. Serial No. 236,629.

To all whom it may concern:

Be it known that I, CHARLES T. CROSBY, a citizen of the United States, residing at Grants Pass, in the county of Josephine and 5 State of Oregon, have invented new and useful Improvements in Igniting Devices, of which the following is a specification.

This invention relates to a match striking device, and has for its object to produce a 10 channeled member of a size to receive therein the head of a match, the said member being provided with one of a plurality of longitudinal grooves the outer edge of which being serrated to provide roughened 15 surfaces against which the head of the match is drawn to ignite the same.

Other objects and advantages will appear as the nature of the invention is better understood, reference being had to the accompanying drawings, in which,

Figure 1 is a fragmentary view of a lantern having the tubular sides for the frame thereof, which provide the air passage, constructed in accordance with this invention.

Fig. 2 is a greatly enlarged transverse sectional view approximately on the line 2—2 of Fig. 1.

Fig. 3 is a front elevation illustrating a modification.

Fig. 4 is a greatly enlarged transverse sectional view approximately on the line 4—4 of Fig. 2.

Fig. 5 is an elevation of a still further modification.

Fig. 6 is a transverse sectional view upon an enlarged scale, and approximately on the line 6—6 of Fig. 5.

Fig. 7 is a front elevation of a still further modification.

Fig. 8 is a transverse sectional view approximately on the line 8—8 of Fig. 7.

Users of lanterns are well acquainted with the difficulties encountered in igniting a match to light the wick of the lantern. The 45 tubular air passages 7 which form the sides of the frame of the lantern 8 preferably are strengthened by having the opposite sides thereof ribbed. The tubes are generally con-

structed from a single member one of the ribs being formed by centrally pressing the 50 sheet outwardly, the other rib being provided by the lapping edges formed on outward portions of the sheet. In some instances the tube is constructed of two semi-cylindrical members, but in no instance is 55 there provided a serrated surface on the tube nor an arcuate longitudinal depression which may serve as a guide for a match head.

In the construction illustrated in Figs. 1 and 2 of the drawings the tube 7 has one or 60 both of its flanges or beads, indicated by the numerals 9, formed upon one of the sides thereof with a longitudinal groove 10, and the said groove is centrally provided with a rib 11, the outer face of this rib is serrated 65 or roughened as at 12. The groove provides a passage for the match head and the same contacting with the serrated rib 12 will be readily ignited.

The device is not to be restricted in its 70 useful employment to lanterns, and in Figs. 3 and 4 of the drawings I have illustrated a plate 13 which is concaved longitudinally or is approximately semi-cylindrical in cross section. One of the ends of this plate may 75 be closed and the other open, but, of course, both ends may be closed or opened as desired. The member 13 is centrally provided with a longitudinal rib 14, the outer edge of which is serrated as at 15, 80 and this serrated edge provides the striking element for the head of the match, the said match being guided by the rounded walls providing the sides of the plate.

In Figs. 5 and 6 the construction is sub- 85 stantially similar to that illustrated in Figs. 3 and 4, the cross sectional semi-cylindrical plate 17 being, however, centrally provided with spaced longitudinal ribs 18, and the outer edges of these ribs are roughened or 90 serrated as at 19.

In Figs. 7 and 8 the concave plate 20 is of a greater cross sectional diameter than those previously described, and is corrugated providing the same with spaced ribs 22 and 95 grooves 23. The sides of the ribs are rough-

ened as at 24, and the match head being drawn between the grooves and contacting with the roughened surfaces 24 will readily ignite.

5 It is believed, from the foregoing description, that the simplicity and advantages of the construction will be apparent without further detailed description.

Copies of this patent may be obtained for five cents each, by addressing the "Commissioner of Patents, Washington, D. C."

Having thus described the invention, what I claim is:

10 In combination with the air tube of a lantern, of a concaved head on the side thereof, a longitudinal rib in said head, and said rib having its outer edge serrated.

15 In testimony whereof I affix my signature.

CHARLES T. CROSBY.
